UNITED STATES PATENT OFFICE.

TOMIE DAVIS, OF LEGGETT, TEXAS.

MAIL-BAG CATCHER.

1,260,521.

Specification of Letters Patent. Patented Mar. 26, 1918.

Application filed June 21, 1917. Serial No. 176,205.

To all whom it may concern:

Be it known that I, TOMIE DAVIS, a citizen of the United States, residing at Leggett, in the county of Polk and State of Texas, have invented certain new and useful Improvements in Mail-Bag Catchers, of which the following is a specification.

My invention relates to improvements in mail bag catchers, and it consists in the 10 constructions, combinations and arrangements herein described and claimed.

An object of my invention is to provide a mail bag catcher including a column mounted in a standard which contains an 15 arrangement of springs whereby the column is normally held in a correct position so that a bag catching jaw carried by an extension of the column may be normally disposed in a mail bag receiving position.

20 Other objects and advantages will appear from the following specification, reference being had to the accompanying drawings, in which:—

Figure 1 is a side elevation showing the 25 principal elements of my device, certain portions being shown in section,

Fig. 2 is a plan view of the parts shown in Fig. 1, portions being shown in section,

30 Fig. 3 is a section of the column supporting standard showing the spring arrangements therein,

Fig. 4 is a cross section on the line 4—4 of Fig. 3, and

Fig. 5 is a cross section on the line 5—5 35 of Fig. 3.

In carrying out my invention I provide a platform 1 which is to be supported upon any suitable foundation as for instance a number of ties 2. The ties 2 as shown in 40 Fig. 1 are considerably longer than the usual ties which support the rails of the tracks, and if in actual practice, it be found inexpedient to employ and arrange the ties as shown in Fig. 1, any other suitable foundation for the platform 1 may be provided.

45 A hollow standard 3 is supported upon the platform 1 by means of an annular flange 4 on the standard 3 through which screws 5 pass and hold the hollow standard 3 firmly in position. A cap 6 closes the top of the standard 3 and by means of an axial opening therein, assists in supporting a column 7 in the standard 3.

The column 7 has a horizontal extension 50 8 as shown in Figs. 1 and 2. A staff 9 is slidably disposed in the extension 8 which

for the purpose is hollow. Set screws 10 bind the staff 9 to whatever position it may be desired to locate the staff.

A fixed jaw 11 is secured upon the outer 60 end of the staff 9 by means of bolts which pass through the fixed jaw plate 11 and through a collar or flange 13 on the end of the staff 9. The fixed jaw plate 11 is normally disposed in parallelism with the direction of travel of the trains upon the roadway, one of the cars of a train being indicated as 14 in Fig. 1. The staff 9 and the supporting extension 8 therefor, are however, disposed at an angle to the fixed jaw 70 plate 11.

The disposition of the extension 8 and the staff 9 at an angle with the fixed jaw plate 11, however has no material advantage but is simply the most effective expedient for 75 properly mounting the fixed jaw plate 11 so that subsequent movement of the extension 8 and staff 9 with the column 7 as an axis, may be compensated for when a mail bag is received by the catcher.

80 A movable jaw plate 15 is fulcrumed as at 16 upon the fixed jaw plate 11. A strong leaf spring 17 which is secured upon the fixed jaw plate 11, bears against the movable jaw plate 15 and tends to urge it toward the plate 11 and thereby to close the jaws of the catcher.

85 Trip links 18 are pivoted as at 19 to the respective movable and fixed jaw plates 15 and 11 respectively. When the trip links 90 18 are extended so that the various pivotal points are in alinement, the movable jaw 15 will be held in the position shown in Fig. 2 in readiness to receive a mail bag. The mail bag is carried by the car 14, and 95 when it strikes the trip links 18, the intermediate pivotal point 19^a will be moved out of alinement with the extreme pivotal points 19 thus "breaking" the trip link connection and permitting the movable jaw 100 plate 15 to close upon the fixed jaw plate 11 by virtue of the tension of the spring 17.

105 A resetting arm 20 is fulcrumed as at 21 upon the movable jaw plate 15. The resetting arm 20 has a roller 22 at its end and also has a lever 23 by which the resetting arm 20 is manipulated by the operator. The arm 20 is adapted to move through a suitably arranged slot 24 in the movable jaw plate 15, when it is desired to bring 110 the movable jaw plate 15 to the position shown in Fig. 2 after the trip links 18 were

collapsed by the striking of a mail bag against them. In this instance, the lever 23 is moved outwardly whereupon the roller 22 will accordingly roll over the surface of the fixed jaw plate 11 and cause the movable jaw plate 15 to move away from the plate 11 and return to the position shown in Fig. 2.

The attendant's platform 25 is located beneath the catching jaws, and is supported by suitable trusses 26. A ladder 27 serves as a mounting for the attendant to the platform 25. When a mail bag is caught by the jaws, the attendant mounts the platform 25 and loosens the bag by operating the resetting arm 20 through the medium of the lever 23 in the manner above described.

A pair of springs 28 and 29 are mounted in the upper and lower portions, respectively of the standard 3. The springs 28 and 29 are adapted to be wound in opposite directions, that is to say when the column 7 is turned to the right, tension is stored in the upper spring 28. When the column 7 is rotated to the left, tension is stored in the lower spring 29. The extreme ends of the springs 28 and 29 are secured to adjacent fixed portions of the standard 3 in any suitable manner.

An annular flange 30 is fixed upon the column 7 intermediate of the ends of the standard 3. Set screws 31 which pass through a collar on the flange 30, serve to secure the flange to the column 7.

The medial ends of the springs 28 and 29 are looped as at 28^a and 29^a, respectively. Pins 32 and 33 on the upper and lower surfaces of the flange 30, coöperate with the respective loops 28^a and 29^a. For instance, when the column 7 is rotated toward the right, the pin 32 will accordingly enter the loop 28^a as shown in Fig. 4 and by winding the spring 28 will store tension therein which will serve to restore the column to its former position and reset the extension 8 to the position shown in Fig. 2.

Should the column 7 be rotated in the other direction, the pin 33 will enter the loop 29^a, as shown in Fig. 5 and store tension in the lower spring 29 which will serve to return the column 7 to its normal position. In winding the springs 28 and 29 and fixing them within the standard 3 in the first instance, it is to be observed that the tension of the respective springs should be such that under normal conditions they will counter-balance one another and serve to maintain the column 7 in such a position that the extension 8 and its carried bag catching jaw will be disposed substantially in the position shown in Fig. 2.

The mail bag 34 is supported by the loops 35 upon the ends 36 of a pair of arms 37.

The arms 37 are journaled in brackets 38 in the doorway 39 of the car 14. The upper arm 37 carries a plunger 40 which is received by a cylinder 41 and is pressed outwardly by a spring 42. The connection of the arms 37 with the brackets 38 is loose enough to permit the extension of the arms 37 within certain confines through the tension of the spring 42. The standard 3 is braced upon the platform 1 by a plurality of guy rods 43 which may be tightened by the turn buckles 44.

The operation of the device is as follows. It has been explained that the tension of the respective springs 28 and 29 is such that they counter-balance one another with the result that the extension 8 with its carried catching jaws, is disposed at the predetermined location illustrated in Fig. 2.

The mail clerk aboard the car 14 hangs the mail bag 34 between the members 36 of the arms 37, and swings the arms 37 to the position shown in Fig. 1. The arms 37 are held in this position by any suitable latch mechanism which does not enter as an element of the present invention. The spring 42 in the cylinder 41 serves to keep the arms 37 extended and consequently will hold the bag 34 in position.

As the car 14 now advances toward the open jaws of the catcher, the bag 34 will strike the trip links 18 and "break" the connection. The spring 17 will now cause the movable jaw plate 15 to move toward the fixed jaw plate 11 and consequently clamp the bag 34 between the jaws.

The attendant upon mounting the platform 25, will operate the resetting arm 20 through the medium of the lever 23 in the manner previously explained and thus release the bag 34 which may then be taken away. The jaws are thus reset and ready to receive another bag.

The impact of the advancing bag 34 into the jaws will cause the extension 8 to move to a certain extent, the column 7 acting as a pivot. When this occurs the pin 32 on the flange 30 will enter the loop 28^a and wind the spring 28. The same forward movement of the extension 8 together with the advancing bag 34 will serve to cause the arms 37 to rotate in their brackets 38 in a direction toward the car 14. As the car 14 continues to advance, the disengagement of the loops 35 of the bag 34 will be finally effected and when this disengagement occurs, the stored tension in the spring 28 will act upon the column 7 and return it to its former position so that the extension 8 and its carried catcher will be located in the position shown in Fig. 2.

While the construction and arrangement of the device as illustrated in the drawings is that of a generally preferred form, obvi-

ously modifications and changes may be made without departing from the spirit of the invention or the scope of the claims.

I claim:—

- 5 1. A mail bag catcher including a hollow standard mounted upon a platform, a column journaled in the standard, a bag catcher carried by said column, a flange carried by the column interiorly of the standard, oppositely wound springs in the standard, these springs having loops adjacent to the flange, and pins on the flange engageable with one or the other of the loops as the column is rotated in one or the other direction.
- 10 2. A mail bag catcher comprising a hollow standard, a column journaled in said standard, a bag catcher carried by said column, oppositely wound springs in said standard, said springs having loops adjacent said column, and pins carried by said column and releasably engageable with one or the other of said loops as the column is rotated in one or the other direction.
- 15 3. A mail bag catcher comprising a hollow standard, a column journaled in said standard, a bag catcher carried by said column, oppositely wound springs in said standard, said springs having loops projecting in opposite directions, and pins carried by said standard and alternately engageable with one or the other loops as the column is rotated in one or the other direction, whereby only the tension of one spring at a time will be increased for returning said journal to its normal position.
- 20 4. A mail bag catcher comprising a hollow standard, a column journaled in said standard, a bag catcher carried by said column, oppositely wound springs in said standard, said springs having loops adjacent said column, and means carried by said column and releasably engageable with one or the other of said loops as the column is rotated in one or the other direction.
- 25 5. A mail bag catcher comprising a hollow standard, a column journaled in said standard, a bag catcher carried by said column, oppositely wound springs in said standard, said springs having receiving portions adjacent said column, and pins carried by said column normally engaging the receiving portions of both the springs, thus normally retaining said column in a set position, and said pins being adapted to disengage one of the receiving portions and draw upon the remaining receiving portion, as the column is swung in one direction, thus increasing the tension of one spring to cause the return of the column as soon as pressure is relieved therefrom, thus causing the pins to again engage both receiving portions for holding the column in a set position as above specified.
- 30 6. A mail bag catcher comprising a hollow standard, a column journaled in said standard, a bag catcher carried by said column, oppositely wound springs in said standard, said springs having receiving portions adjacent said column, and pins carried by said column and releasably engageable with one or the other of said receiving portions as the column is rotated in one or the other direction.
- 35 7. In a mail bag catcher comprising a hollow standard, a column journaled in said standard, a bag catcher carried by said column, oppositely wound springs in said standard, having loops adjacent said column, and means carried by said column and normally engaging both of said loops, thus holding the column in a normal position, said means adapted to disengage one loop and draw upon the remaining loop for winding one spring as the column is swung in one direction, thus causing the column to be returned to its normal position with the means engageable with both of said loops when the pressure thereon is relieved.
- 40 8. In a mail bag catcher comprising a hollow standard, a column journaled in said standard, a bag catcher carried by said column, oppositely wound springs in said standard, said springs having receiving portions adjacent said column, and pins carried by said column normally engaging the receiving portions of both the springs, thus normally retaining said column in a set position, and said pins being adapted to disengage one of the receiving portions and draw upon the remaining receiving portion, as the column is swung in one direction, thus increasing the tension of one spring to cause the return of the column as soon as pressure is relieved therefrom, thus causing the pins to again engage both receiving portions for holding the column in a set position as above specified.
- 45 9. A mail bag catcher comprising a hollow standard, a column journaled in said standard, a bag catcher carried by said column, oppositely wound springs in said standard, having receiving portions adjacent said column, and engaging means carried by said column and normally engaging the receiving means of said springs, thus causing the column to be normally retained in a set position, said pins being adapted to disengage one of the receiving portions and to draw upon the remaining receiving portion to increase the tension of one spring, thus causing the column to be returned to its normal position as soon as pressure is relieved from the bag catcher, thus causing the engaging means to again engage both receiving portions for again holding the column in its normal position.
- 50 10. A mail bag catcher comprising a hollow standard, a column journaled in said standard, a bag catcher carried by said column, tension means in said standard having receiving portions engaging said column, pins carried by said column, and normally engaging the receiving portions, thus causing the column to be held in a set position, said pins being adapted to disengage one receiving portion to draw upon another receiving portion, for causing the return of the

column to its normal position after pressure is relieved therefrom, at which time said pins will again engage the receiving portions for again holding said column in a set position.

11. A bag catcher comprising a hollow standard, a column journaled in said standard, a bag catcher carried by said column, tension means carried within said standard and having receiving portions adjacent said column, and engaging means carried by said column and normally engaging the receiving portions for retaining said column in a set position, said column being adapted to rotate as pressure is applied thereto, thus caus-

ing the engaging means to disengage one of the receiving portions and move the remaining receiving portions to actuate one of the tension means, thus causing the column to be returned to its normal position for causing the engaging means to again engage the receiving portions for again retaining the column in its normal position. 20

In testimony whereof I affix my signature in presence of two witnesses.

TOMIE DAVIS.
